his Attorney.

UNITED STATES PATENT OFFICE

2,291,956

ELECTRICALLY BONDED RAIL JOINT

Harold H. Febrey, South Orange, N. J., assignor
to The American Steel and Wire Company of
New Jersey, a corporation of New Jersey

Application May 14, 1940, Serial No. 335,182

2 Claims. (Cl. 238—14.9)

This invention relates generally to electrically bonded rail joints and is particularly concerned with the type including a bond having terminals fixed to the tops of the flanges of the adjacent ends of aligned railroad rails which are joined by a splice bar providing a flange overlying these rail flange tops, the bond terminals being fixed to the rail flange tops beyond the ends of the splice bar and a conductor made of stranded wires being fixed to these terminals and extending over top of the splice bar flange.

A rail joint splice bar is cut from a long rolled section, the cutting providing the splice bar with sharp corners at its ends including the top corners of its flange over which the conductor of the bond of a joint of the type described must pass. This presents a problem in that dragging train equipment or derailed train wheels which press downwardly on the conductor cause it to be sheared against the sharp top corners of the splice bar ends.

A bonded rail joint constructed in accordance with the present invention solves the above problem and, in addition, permits the provision of a cheaper bond for the joint without sacrificing its electric conductivity when the bond is made with steel terminals and the conductor is made of copper.

Such a bond is illustrated by the accompanying drawing in which:

Figure 1 is a side view of a rail joint electrically bonded by the bond; and

Figure 2 is a horizontal section of the same taken from the line II—II in Figure 1.

More specifically, these drawings show the adjacent ends of aligned railroad rails 1 and 2, these ends being joined by a splice bar 3 having a flange 4 overlying the flanges 1^a and 2^a of the rails. The top corners 4^a of the ends of this splice bar are relatively sharp.

The rail bond terminals 5 are welded to the tops of the rail flanges 1^a and 2^a close to the ends of the splice bar flange 4. These terminals are novel in that they are made of steel and have solid shanks 5^a rising from the rail flanges 1^a and 2^a, these shanks bending in the direction of each other over and beyond the splice bar ends after they rise above the latter. The conductor 6 is butt-welded to the ends of these shanks and is made of intertwined copper wires.

Dragging train equipment or derailed train wheels riding along the tops of the rail flanges, ride over the solid steel shanks 5^a when they encounter the bond terminals, it being these solid steel shanks that are pressed against the sharp

corners of the splice bar ends. Due to the sturdiness and strength of these solid steel shanks, the bond is not put out of service as it would be in the case of the conventional bonded joint. That is to say, the conventional arrangement wherein the terminals are welded to the tops of the rail flanges a greater distance beyond the splice bar ends with the conductor made of intertwined copper wires extending over these splice bar ends, is generally put out of service in the event of such accidents since the conductor is placed in shear against the sharp corners of the splice bar ends.

A bond of the type illustrated is normally used as a power bond, and the total resistance of the joint is carefully calculated as an important factor in the design of the road. Due to the fact that the present invention contemplates the use of steel terminal shanks which are considerably longer than is conventional, and since steel is less conductive than copper, those skilled in the art might normally suppose that the electrical resistance of the bonded joint would be greater than that of a joint embodying the conventional bond. However, it has been discovered that the terminals illustrated involve such a shortening of the conductor by virtue of their being placed so close to the splice bar ends, and by virtue of the length of their shanks, as to result in the resistance of the joint being about the same as one embodying the conventional bond involving the serious disadvantage of having its conductor lying directly over the sharp corners of the splice bar ends.

I claim:

1. An electrically bonded rail joint comprising the combination of aligned railroad rails having their adjacent ends joined by a splice bar providing a flange overlying adjacent portions of the rail flanges and having sharp top corners at its ends, rail bond terminals fixed to the tops of the rail flanges close to the ends of the splice bar flange and having solid metal shanks rising from the rail flanges and bending in the direction of each other over and beyond the top corners of the splice bar ends, and a stranded, electrical conductor interconnecting the ends of the rail bond terminal shanks, the latter being sufficiently strong to withstand being forced against the sharp top corners of the ends of the splice bar flange by equipment dragging from passing trains.

2. An electrically bonded rail joint comprising the combination of aligned railroad rails having their adjacent ends joined by a splice bar providing a flange overlying adjacent portions of the

5 rail flanges and having sharp top corners at its ends, rail bond terminals fixed to the tops of the rail flanges close to the ends of the splice bar flange and having solid metal shanks rising from the rail flanges and bending in the direction of each other over and beyond the top corners of the splice bar ends, and a stranded, electrical conductor interconnecting the ends of the rail bond terminal shanks, the latter being sufficiently strong to withstand being forced against the 10 sharp top corners of the ends of the splice bar

flange by equipment dragging from passing trains, the rail bond terminal shanks being made of steel and the conductor being made of copper, the conductor length being correlated to the length of the steel terminal shanks so the electrical resistance of the joint is no greater than that of a similar joint having shorter steel terminal shanks with the terminals fixed to the rail flanges farther from the splice bar ends and necessarily using a longer copper conductor.

HAROLD H. FEBREY.
